FIRE AND WATER TUBE BOILER

Charles F. R. Stallbaum, Everett, Wash., assignor to Charles Williams as trustee of thirty-two and one-third per cent for himself, thirty-three and one-third per cent for Victor L. Tote, and thirty-four and one-third per cent for said Stallbaum

Application July 1, 1946, Serial No. 689,711

4 Claims. (Cl. 122—43)

1

This invention relates to a boiler or steam generator and an object of this invention is to provide a boiler that is highly efficient in the generation of steam and economical in fuel consumption.

Another object is to provide a boiler having a large area of exposed heat exchange surface so that steam can be quickly generated therein.

Another object is to provide a boiler of strong and durable construction that is reliable and safe in operation.

Another object is to provide a tube type boiler in which the heated gases not only pass through the tubes of the boiler but also pass around and contact the outside shell of the boiler.

Another object is to provide a boiler in which the water and steam passes through a plurality of closely spaced pipes or tubes which are positioned in the path traversed by the hot gases on their way from the boiler tubes to the flue so that much of the heat remaining in these gases will be picked up and utilized.

Another object is to provide a steam generator in which the hot water from the boiler passes first into a hot water drum and then by way of a plurality of small closely spaced conduits into a steam drum and in which the hot water drum and steam drum are positioned parallel to each other so that large surface areas on both of said drums are available for the attachment thereto of a very large number of conduits of small diameter which extend across the path of the heated gases that have passed over and through the boilers.

The above mentioned general objects of my invention, together with others inherent in the same, are attained by the mechanism illustrated in the following drawings, the same being preferred exemplary forms of embodiment of my invention, throughout which drawings like reference numerals indicate like parts:

Figure 1 is a side elevation of a boiler constructed in accordance with my invention, parts being shown by dotted lines;

Fig. 2 is a front elevation of said boiler, parts being shown by dotted lines and parts being broken away to more clearly show other parts within the boiler housing;

Fig. 3 is a sectional view on a larger scale of said boiler taken substantially on broken line 3—3 of Fig. 2;

Fig. 4 is a fragmentary sectional view showing means used to connect a water drum to a boiler housing or shell; and

Fig. 5 is a fragmentary sectional view illus-

trating a preferred method of making a boiler housing or shell and a preferred manner of attaching the end portions of tubes to the head or crown sheet of said boiler shell.

5 This steam generator comprises a housing 7 of refractory material, such as fire brick. Two boiler shells 8 and 9 of fire tube type are supported in side by side horizontally spaced apart relation in the housing 7. Preferably generally upright supporting members 10 are used to support the two shells 8 and 9.

An upright baffle wall 11 of refractory material extends crosswise of the housing 7 near the front ends of the boiler shells 8 and 9. Preferably the 15 upper portion of this baffle wall is suitably shaped to fit the contour of the boiler shells 8 and 9. Preferably this baffle wall 11 terminates a short distance above a horizontal plane that is tangent to the lowermost portions of the two boiler shells 8 and 9, see Fig. 2.

A combustion chamber 12 (see Fig. 3) is provided in front of the baffle wall 11 and heat generating means, such as one or more oil burners 13, are provided to maintain combustion. A 20 chamber 14 for the circulation of heated gases is provided within the housing 7 to the rear of the boiler shells 8 and 9.

In constructing the boiler shells 8 and 9 the end portions or crown sheets 15 thereof are preferably each made in the shape shown in Fig. 5, and these end portions are secured to the medial cylindrical portions of the shells by butt welds 16.

35 A plurality of fire tubes or flues 17 extend lengthwise of each boiler shell 8 and 9. Preferably, the end portions of these tubes 17 extend through externally counterbored holes 18 in the crown sheets 15 and are expanded in the holes 18 and have their extremities upset to form 40 beaded portions 19 that are swaged over or clinched into the counterbored portions 20 of the holes 18.

Each boiler shell 8 and 9 has a manhole 21 provided in the bottom portion thereof. Each man hole 21 is closed and sealed by a removable man hole cover 22. Also a wash out plug 23 is 45 preferably provided in one end of each boiler shell 8 and 9. In Figs. 2 and 3 the lowermost fire tube 17 is omitted from each boiler shell and the wash out plug 23 is provided in the rear crown sheet 15 in place of this lowermost tube 17. In order to reinforce the front head or crown sheets 15 of the shells 8 and 9, a "belly" brace is provided which comprises a bracket 24 welded to the said shells 8 and 9 (8 being shown in Fig. 3). A

flexible stay bolt 25 is provided with a round head 26 and at the other end with a threaded portion 27. The round head 26 of the bolt 25 interfits with a recess in the bracket 24. The threaded portion 27 interfits with threads in an opening in the crown sheets 15. After the stay bolt 25 has been positioned, preferably the end thereof is cut flush with the outer surface of sheets 15 and the outer surface welded. Sliding and turning movement between the bracket 24 and the end portion of 25 toward head 26 is permitted during expansion and contraction and thus the stay bolt is termed a flexible stay bolt.

A cylindrical hot water drum 28 is positioned on top of the two boiler shells 8 and 9 and extends crosswise thereof at a location preferably about one-third of the distance from the front to the rear end of said shells. The hot water drum 28 is communicatively connected with each shell 8 and 9. Preferably the connections between these parts are made, see Fig. 4, by providing a flange 29 on shells 8 and 9 (shell 9 being shown in Fig. 4) which registers with a flange 30 on drum 28. These flanges 29 and 30 are provided with machined surfaces which are positioned in abutting relation. A plurality of rivets 31 interconnect flanges 29 and 30. The flange 29 has a shoulder 33. A tube or pipe 32 extends through an opening in the flanges 29 and 30 and against the shoulder 33. The tube 32 is expanded to be held in place.

Preferably the ends of the hot water drum 28 (see Fig. 2) overhang the side walls of the housing 7 and are supported thereon. Also, preferably a man hole is provided in one end of the drum 28 and is closed by a man hole cover 34 (see Fig. 1).

A steam drum 35 is supported at the rear of the housing 7, crosswise of said housing 7 and parallel with the hot water drum 28 and at a higher elevation than said hot water drum 28.

A plurality of pipes or conduits 36 connect the hot water drum 28 with the steam drum 35. These pipes 36 are connected at one end with the upper half of the hot water drum 28 and at the other end with the lower half of the steam drum 35. All of these pipes have an upward incline from the hot water drum 28 to the steam drum 35. Where it is necessary, these pipes 36 are bent at the locations where they are connected with the two drums 28 and 35 but all bends in these pipes are made on an easy and gradual curvature.

The two drums 28 and 35 are parallel to each other and are of large enough size so that there is ample surface area on these drums for the connection therewith of a large number of the conduits 36. These pipes 36 are relatively close together and extend across the path traversed by the heated gases and by products of combustion on their way from the boilers to a smoke stack or flue 37.

The steam drum 35 is preferably provided, at one end, with a man hole having a removable cover 38. Also the uppermost portion of this steam drum 35 is provided with a safety valve 39, and a steam draw off conduit 40 (fragments of each being shown in Fig. 2). A feed water inlet pipe 41 is connected with the steam drum 35. The safety valve 39 and steam draw off pipe 40 are connected with the top portion of the steam drum 35. The feed water inlet pipe 41 is preferably connected with one end portion of the steam drum 35 about half way between the top and bottom of said steam drum. Water is sup-

plied to the feed water inlet pipe 41 under sufficient pressure to force it into the steam drum 35 and preferably at a temperature of about 180° Fahrenheit. The water level of the system is maintained with the water in drum 35 at approximately the middle thereof. Either a sight water level gauge (not shown) is provided for manual operation or an automatic means (not shown) is employed to automatically maintain the desired water level.

A water circulation pipe 42 is connected with the lower portion of the steam drum 35 and extends downwardly through one wall of the housing 7 and thence across said housing 7. Two upright pipes 43 and 44 connect the pipe 42 with the lower portions of the respective boiler shells 8 and 9. A valve 45 is provided in the water circulation pipe 42 between the steam drum 35 and the boiler shells 8 and 9. A blow out valve 46, a fragment of which is shown in Fig. 2, is connected with the pipe 42 externally of the housing 7 and beyond the location where the pipe 42 is connected with the boiler shells 8 and 9.

Preferably at least one inspection door 47 is provided in the rear end of the boiler housing 7.

In the operation of this steam generator, the heated products of combustion pass both through the fire tubes 17 and around the boilers 8 and 9 for heating the water in the boilers 8 and 9. The water thus heated rises into the hot water drum 28 and thence passes through the conduits 36, where most of this water is evaporated into steam, and into the steam drum 35. The steam collects in the top portion of the steam drum 35 and can be drawn off through the conduit 40. Hot water from the steam drum 35 passes through the water circulation pipes 42, 43, and 44 into the boilers 8 and 9.

The conduits 36 wherein most of the steam is formed are many in number, are of relatively small diameter, and extend across the path traversed by the heated combustion products after they leave the boilers 8 and 9. These conduits 36 thus operate efficiently in generating steam and in utilizing the heat remaining in the discharging combustion products.

Obviously, changes may be made in the forms, dimensions, and arrangement of the parts of my invention, without departing from the principle thereof, the above setting forth only preferred forms of embodiment.

I claim:

1. A steam generator comprising a horizontal fire tube boiler having passageways therethrough and therearound; combustion type heating means at one end of said boiler; means at the other end of said boiler providing an outlet passageway for heated combustion gases that have passed through and around said boiler; a hot water drum extending across the top of said boiler at one side of said gas outlet passageway and communicating with said boiler; a steam drum positioned substantially parallel with and above the level of said hot water drum and at the opposite side of said gas outlet passageway; and a plurality of conduits of relatively small diameter communicatively connecting said two drums and extending across said gas outlet passageway.

2. A steam generator comprising a plurality of side by side parallel horizontal fire tube boilers having passageways therethrough and therearound; combustion type heating means at one end of said boilers; means at the other end of said boilers providing an outlet passageway for heated combustion gases that have passed

through and around said boilers; a hot water drum extending across the top of said boilers at one side of said gas outlet passageway and communicating with all of said boilers; a steam drum positioned substantially parallel with and above the level of said hot water drum and at the opposite side of said gas outlet passageway; and a plurality of conduits of relatively small diameter communicatively connecting said two drums and extending across said gas outlet passageway.

3. A steam generator comprising a horizontal fire tube boiler having passageways therethrough and therearound; combustion type heating means at one end of said boiler; means at the other end of said boiler providing an outlet passageway for heated combustion gases that have passed through and around said boiler; a hot water drum extending across the top of said boiler and communicating with said boiler; a steam drum positioned substantially parallel with and above the level of said hot water drum and at the opposite side of said gas outlet passageway; feed water inlet means communicating with said steam drum; water circulating conduit means connecting said steam drum and said boiler.

4. A steam generator comprising a housing; a plurality of horizontal parallel fire tube type boilers in said housing supported in spaced relation from each other and from the walls of said housing and having passageways therethrough and therearound; means forming a combustion chamber forwardly of said boilers communicat- ing with said passageways; said means including

a transverse baffle wall adjacent the front ends of said boilers extending from the bottom of said housing upwardly to a point a short distance above the bottom plane of said boilers, a fuel burner in said combustion chamber, whereby heated products of combustion will be directed upwardly and caused to pass around the outside of said boilers and through the fire tubes of said boilers; means at the rear ends of said boilers providing an outlet passageway for heated combustion gases that have passed through and around said boilers; a hot water drum extending across the top of said boilers and communicating with said boilers; a steam drum positioned substantially parallel with and above the level of said hot water drum and at the opposite side of said gas outlet passageway from said hot water drum; and a plurality of conduits communicatively connecting said two drums and extending across said gas outlet passageway.
